The ornamental design for a flow meter as shown and described.

DESCRIPTION

FIG. 1 is an upper perspective view of a flow meter according to an aspect of the present disclosure.

FIG. 2 is a bottom perspective view of the flow meter in FIG. 1.

FIG. 3 is an elevated right side view of the flow meter in FIG. 1.

FIG. 4 is an elevated left side view of the flow meter in FIG. 1.

FIG. 5 is a top plan view of the flow meter in FIG. 1.

FIG. 6 is a cross-sectional view of the flow meter in FIG. 1 taken along line VI-VI in FIG. 5.

FIG. 7 is a cross-sectional view of the flow meter in FIG. 1 taken along line VII-VII in FIG. 5.

FIG. 8 is a bottom plan view of the flow meter in FIG. 1.

FIG. 9 is an elevated front view of the flow meter in FIG. 1.

FIG. 10 is an elevated rear view of the flow meter in FIG. 1.

FIG. 11 is an upper perspective view of a flow meter according to a second embodiment of the present disclosure.

FIG. 12 is a bottom perspective view of the flow meter in FIG. 11.

FIG. 13 is an elevated right side view of the flow meter in FIG. 11.

FIG. 14 is an elevated left side view of the flow meter in FIG. 11.

FIG. 15 is a top plan view of the flow meter in FIG. 11.

FIG. 16 is a cross-sectional view of the flow meter in FIG. 11 taken along line XVI-XVI in FIG. 15.

FIG. 17 is a cross-sectional view of the flow meter in FIG. 11 taken along line XVII-XVII in FIG. 15.

FIG. 18 is a bottom plan view of the flow meter in FIG. 11.

FIG. 19 is an elevated front view of the flow meter in FIG. 11.

FIG. 20 is an elevated rear view of the flow meter in FIG. 11.

FIG. 21 is an upper perspective view of a flow meter according to a third embodiment of the present disclosure.

FIG. 22 is a bottom perspective view of the flow meter in FIG. 21.

FIG. 23 is an elevated right side view of the flow meter in FIG. 21.

FIG. 24 is an elevated left side view of the flow meter in FIG. 21.

FIG. 25 is a top plan view of the flow meter in FIG. 21.

(Continued)

FIG. 26 is a cross-sectional view of the flow meter in FIG. 21 taken along line XXVI-XXVI in FIG. 25.

FIG. 27 is a cross-sectional view of the flow meter in FIG. 21 taken along line XXVII-XXVII in FIG. 25.

FIG. 28 is a bottom plan view of the flow meter in FIG. 21. FIG. 29 is an elevated front view of the flow meter in FIG. 21.

FIG. 30 is an elevated rear view of the flow meter in FIG. 21.

FIG. 31 is an upper perspective view of a flow meter according to a forth embodiment of the present disclosure. FIG. 32 is a bottom perspective view of the flow meter in FIG. 31.

FIG. 33 is an elevated right side view of the flow meter in FIG. 31.

FIG. 34 is an elevated left side view of the flow meter in FIG. 31.

FIG. 35 is a top plan view of the flow meter in FIG. 31.

FIG. 36 is a cross-sectional view of the flow meter in FIG. 31 taken along line XXXVI-XXXVI in FIG. 35.

FIG. 37 is a cross-sectional view of the flow meter in FIG. 31 taken along line XXXVII-XXXVII in FIG. 35.

FIG. 38 is a bottom plan view of the flow meter in FIG. 31.

FIG. 39 is an elevated front view of the flow meter in FIG. 31.

FIG. 40 is an elevated rear view of the flow meter in FIG. 31.

FIG. 41 is an upper perspective view of a flow meter according to a fifth embodiment of the present disclosure. FIG. 42 is a bottom perspective view of the flow meter in FIG. 41.

FIG. 43 is an elevated right side view of the flow meter in FIG. 41.

FIG. 44 is an elevated left side view of the flow meter in FIG. 41.

FIG. 45 is a top plan view of the flow meter in FIG. 41.

FIG. 46 is a cross-sectional view of the flow meter in FIG. 41 taken along line XLVI-XLVI in FIG. 45.

FIG. 47 is a cross-sectional view of the flow meter in FIG. 41 taken along line XLVII-XLVII in FIG. 45.

FIG. 48 is a bottom plan view of the flow meter in FIG. 41.

FIG. 49 is an elevated front view of the flow meter in FIG. 41.

FIG. 50 is an elevated rear view of the flow meter in FIG. 41.

FIG. 51 is an upper perspective view of a flow meter according to a sixth embodiment of the present disclosure. FIG. 52 is a bottom perspective view of the flow meter in FIG. 51.

FIG. 53 is an elevated right side view of the flow meter in FIG. 51.

FIG. 54 is an elevated left side view of the flow meter in FIG. 51.

FIG. 55 is a top plan view of the flow meter in FIG. 51.

FIG. 56 is a cross-sectional view of the flow meter in FIG. 51 taken along line LVI-LVI in FIG. 55.

FIG. 57 is a cross-sectional view of the flow meter in FIG. 51 taken along line LVII-LVII in FIG. 55.

FIG. 58 is a bottom plan view of the flow meter in FIG. 51. FIG. 59 is an elevated front view of the flow meter in FIG. 51; and,

FIG. 60 is an elevated rear view of the flow meter in FIG. 51.

The broken lines in the figures are for contextual purposes or show the environment and form no part of the claimed design.

The portion between the pair of closely adjacent, spaced, jagged, broken lines in the drawings are broken away to indicate no particular length or width of the portion of the flow meter and such pairs of jagged, broken lines themselves form no part of the claimed design. The material that may be visible between the jagged lines has been removed for clarity.
